UNITED STATES PATENT OFFICE.

BLACK SMITH E. TAKKEN, OF HOLLAND, MICHIGAN.

AXLE-BOX.

SPECIFICATION forming part of Letters Patent No. 663,189, dated December 4, 1900.

Application filed April 7, 1900. Serial No. 11,943. (No model.)

To all whom it may concern:

Be it known that I, BLACK SMITH E. TAKKEN, a citizen of the United States, residing at Holland, in the county of Ottawa and State 5 of Michigan, have invented certain new and useful Improvements in Axle-Boxes, of which the following is a specification.

My invention relates to an improvement in axle-boxes; and its object is to provide an 10 improved construction of axle-box and wheel-securing means whereby dust and dirt are entirely excluded from the axle-bearing.

The construction of the improvement will be fully described in connection with the accompanying drawing and its novel features 15 defined in the appended claims.

The drawing represents a longitudinal section of an axle, axle-box, and securing means embodying the invention.

20 The reference-numeral 1 designates the axle-spindle, formed with a central longitudinal oil-passage 2, extending from the outer end of the spindle to about the center thereof and communicating at its inner end with a 25 transverse oil-passage 3.

25 4 designates the axle-box fitting over the spindle and externally threaded at its outer end to receive an internally-threaded cap 5, having a central threaded opening 6, registering with the outer end of the oil-passage 2 and adapted to be closed by a screw-plug 7.

30 The inner end 8 of the box 4 is circumferentially enlarged and externally threaded to be engaged by the internally-threaded flange 35 9 of an inner cap 10.

35 The inner surface of the end 8 of the axle-box is formed with an annular recess 11, within which fits a collar 12, formed integral with a sleeve 13, which extends through the cap 10 40 and is secured to the spindle by a transverse pin or bolt 14. The outer surface or shoulder 15 of the collar is overlapped by the cap 10.

45 16 designates a set-screw extending through an internally-threaded horizontal opening 17 in the cap 10 and adapted to impinge against the inner edge of the axle-box, as shown, to compensate for wear.

Oil is supplied to the passages 2 and 3 by removing the plug 7, and the oil finds its way to the space between the spindle and axle- 50 box, as will be apparent.

As the outer ends of the box and spindle are closed by the cap 5 and the inner end of the box by the collar 12 and cup 10, the latter overlapping the former, dust and dirt are excluded from the axle-box and the free revolution of the axle-box and wheel is insured. 55

I claim—

1. The combination with an axle-spindle formed with a longitudinal oil-passage connecting with a transverse passage, of a box surrounding the spindle and externally threaded at its outer end; an internally-threaded cap formed with a central opening; a screw-plug for closing the opening in the 65 cap; a sleeve secured to the spindle and fitting an annular recess formed in the inner end of the axle-box, and a cap for closing the inner end of the box.

2. The combination with an axle-spindle 70 formed with a longitudinal oil-passage; of a box surrounding the spindle, said box being externally threaded at its outer end, and circumferentially enlarged and externally 75 threaded at its inner end; an internally-threaded cap fitting over the outer end of the box, and having a central opening; a screw-plug for closing said opening; a sleeve secured to the spindle and having a collar fitting an annular recess at the inner end of the 80 box; a cap fitting against the inner end of the box and overlapping said collar, and having an internally-threaded flange which engages the threads on the box; and a set-screw extending through the inner cap and adapted 85 to impinge against the inner end of the box.

In testimony whereof I affix my signature in presence of two witnesses.

BLACK SMITH E. TAKKEN.
